THEATER SEAT HINGE

Milford T. Vandervoort, Saginaw, Mich., assignor
to American Seating Company, Grand Rapids,
Mich., a corporation of New Jersey

Application November 3, 1938, Serial No. 238,497

12 Claims. (Cl. 155—86)

This invention relates to hinges for seats, and is more particularly concerned with a hinge construction for theater seats for mounting the folding seat member upon supporting standards in a novel and practical manner. The present invention is concerned with many improvements in and with relation to the theater seat hinge structure shown in my prior Patent No. 2,070,387, issued February 9, 1937.

The present invention has for its object and purpose the provision of a seat hinge of the type stated, wherein the hinge parts have a substantially universal movement with respect to each other, permitting the standards on which one member of the hinge is connected to be disposed at various angles with respect to the folding seat upon which the other member of the hinge is permanently secured. Such universal movement permits the installation of rows of seats with consecutive spaced apart standards in the row, each serving to carry one side of each of two folding seats, and with the row of seats disposed in a curved form, such as the arc of a circle or otherwise and with any desired variation in the radius of curvature of the arc of any row or of different rows of the seats. A further object of the invention is to provide a construction which is very economical to produce, substantially all parts being readily formed from sheet metal and stamped or pressed to shape, and with the assembly of the parts being easy and economical.

Many other objects and purposes of the invention will appear as an understanding of the invention is had from the following description, taken in connection with the accompanying drawings, in which:

Fig. 1 is a fragmentary front elevation illustrative of the location of a plurality of theater seats in a row, one of the seats being shown completely between two spaced apart supporting standards.

Fig. 2 is a vertical section from front to rear, showing the mounting of the seat.

Fig. 3 is a fragmentary enlarged vertical section and side elevation illustrating the position of the seat when in its lower substantially horizontal operative position.

Fig. 4 is an elevation looking at the hinge structure with the supporting bracket for a side of the seat removed.

Fig. 5 is a transverse vertical section through the hinge.

Fig. 6 is a longitudinal vertical section therethrough, and

Fig. 7 is a perspective view of the parts comprising one of the hinge members which hinge member in use is connected to a side of a standard.

Like reference characters refer to like parts in the different figures of the drawings.

The vertical standards 1 for supporting the theater or similar seats are spaced apart from each other, and between any two adjacent standards the folding seat 2 is located in front of a substantially vertical back 3, the backs of the seats being secured between any two consecutive standards in any well-known and conventional manner. The folding seat members 2 have sheet metal brackets connected one at each side and at the inner ends thereof. The brackets are of an angle form having two legs 4 and 5 disposed at right angles to each other. The legs 4 extend underneath the inner or rear portions of the seat, while the legs 5 extend along opposite side edges of the seat member 2, as shown.

The standards at opposite sides thereof, where a row of standards are used, or at the inner sides where only two standards and a single seat are assembled together, have rectangular flat metal plates 6 secured thereto. A tubular sleeve 7 at each end is provided with projecting lugs 8. Said lugs 8 at one end of the member 7 pass through suitable openings provided therefor in the plate 6 and are riveted over at their ends to permanently connect the plate 6 and the tube 7 together. At the opposite end of the tube 7 a flat plate is permanently secured in the same manner, the central portion of which is pressed toward the plate 6 to make a cup 9. Four arms 10 and 11 in opposed pairs extend outwardly from the central cup-like portion 9 of the plate, the arms 10 and 11 being at right angles to each other and the arms 10 being wider than the arms 11. The cup 9 is adapted to have one end of a coiled compression spring 12 inserted therein, the other end of which, in the assembled hinge, bears against the leg 5 of the adjacent bracket secured to the folding seat 2 (Fig. 6). Two curved bearing shoes 13 made of flat metal, covered at their outer curved surfaces with curved fiber members 13a, are disposed around the outer edges of the arms 10 and 11, each being substantially of semi-circular form so that the free ends of the shoes 13 approach and come closely adjacent to each other between the side edges and at the ends of the arms 10. At the inner side of each of the shoes 13 a channel member having a web 14 and inwardly extending spaced flanges 15 is permanently secured, the ends of the arms

11 entering said channels between the flanges 15. A cup-like housing having a cylindrical opening 18 larger in diameter than the exterior diameter of the tubular member 7, receives the bearing shoes 13 with the fiber bearing portions 13a at their outer sides, located within and against the cylindrical wall 16 of the housing. The tube 7 with the plate secured at one end thereof may then be inserted with the arms 11 of the plate received between the flanges 15 of the channels and the tube 7 passed through the opening at 18, after which the plate 6 may be secured to the opposite end of the tube 7. Or, the plate 6 with the tube 7 attached may be inserted through the opening 18 and the arms 10 of the plate within the housing then secured to the inner end of the tube 7. Either method of assembly may be used. The housing member, comprising the cylindrical wall 16 and the end 17 with the opening 18 therein is permanently secured to the leg 5 of a seat carrying bracket. As shown in Fig. 6, the housing at the end thereof coming to said leg 5 is provided with an outwardly turned annular flange which lies against the leg 5 of the bracket and may be spot-welded or otherwise rigidly secured in place. The spring 12 is placed with one end in the cup 9 prior to the attachment of the cylindrical housing to said leg 5 of the bracket.

15 The tendency of the spring 12 is to move the hinge member consisting of the sleeve 7 and the attached plates longitudinally away from the flange 5. But in assembling the seat with the standards, the springs 12 are compressed in order to enter the plates 6 between the standards, after which said plates 6 are bolted or otherwise secured to the standards 1 with the springs 12 held under compression.

20 As shown in Fig. 5, two stops 19 are permanently secured to and at the inner side of the end 17 of the housing, against one end of each of which one of the flanges 15 of the channel members comes when the seat is in its lower position, and against the other end of each of which the opposite flanges 15 engage when the seat is turned to vertical position, the swing of the seat being slightly less than 90° or from a substantially vertical to a substantially horizontal position, the seat however, not being carried down entirely to a horizontal position, but being inclined somewhat upwardly and outwardly when in its lower position, as appears in Fig. 3.

25 The housing wall 16 being fixed on the seat and the cylindrical member 7 being fixed on the standard, the turning of the seat between its two positions is accomplished by the rotation of the seat (with the housing) on the shoes 13, 13a held by the channels 14, 15 on the short arms 11 of the plate which is fastened at 8 on the cylindrical member 7. The sleeve 7 may be positioned at an angle so that its axis will not be parallel to or coincide with the cylindrical axis of the wall 16, without in any way disturbing the rotating or turning movement which occurs when the seat is moved between its two positions. The short arms 11 may be sufficiently loose in the channels' webs 14 and between their flanges 15, and the curved outer ends of the long arms 10 may be rounded cross-sectionally (as shown in Figure 6). The springs 12 are available to have varying degrees of compression applied thereto whereby it is not necessary that the standards 1 between which the folding seat 2 is located shall have an exact predetermined distance between them, said

30 springs 12 compensating for a considerable variation. The bearing shoes 13, 13a are held outward against the inner sides of the cylindrical wall 16 of the housing, being located around the outer curved edges of the arms 10 and at the outer ends of the arms 11, described. The assembly of the seats and hinges with the standards is very readily and easily performed.

35 In the cylindrical wall 16 of the housing described, a slot 20 is cut, approximating 90° in length, through which a pin 21 extends, which pin may be an extension of one of the rivets securing a channel member 14, 15 to a curved shoe 13 (Fig. 5).

40 One end of a flat spring metal member 22 is hooked over the pin 21, underneath which member is a length of fiber 23 likewise hooked over the pin and disposed between the member 22 and the outer side of the cylindrical wall 16. The member 22 is of spring material so as to bend readily and conform when necessary to the curvature of the outside of the wall 16. A coiled tension spring 24 is secured at one end to the opposite end of the member 22, and has connection with an angle bracket 25 riveted or otherwise permanently fixed on the leg 5 of the seat supporting bracket, the connection being through a screw 26 which passes through an outturned end of the bracket 25 and threads into a nut 27 connected with the opposite end of the spring 24. It is evident that by operating the screw 26, the tension of the spring 24 may be adjusted.

45 When a seat is moved to lower substantially horizontal position, the spring 24 is stretched, storing power to lift the seat to upper position when released. The bearing of the spring member 22 and the fiber member 23 beneath it on the outer curved side of the wall 16, provides a friction brake which prevents the seat from violently returning to its upper position as shown in Fig. 2, when released. As shown in Fig. 1, the spring 24 is applied to one of the two hinge members only used with a seat 2, though it is to be understood that such return spring construction may be applied to both hinges if desired.

50 The construction of hinge described is economical to produce, the parts are readily and easily fabricated mainly from flat metal, and the connection of the parts together and their assembly is very simply and easily performed. All of the advantages recited in my prior Patent No. 2,070,387, are retained and with the production of a stronger and much more economical construction, eliminating all castings and the machining thereof.

55 The invention is defined in the appended claims and is to be considered comprehensive of all forms of structure coming within the scope thereof, and is not to be limited to specific details of construction shown, other than necessitated by the terms of said claims.

I claim:

60 1. A hinge for theater seats or the like comprising, a member which includes a vertical leg adapted to be secured to a seat, a cylindrical housing fixed to said vertical leg having an outer end with a central opening therethrough, a cylindrical member extending through said opening, bearing shoes of substantially semi-cylindrical form within said housing bearing against the inner sides of the wall thereof, a plate connected to the inner end of said cylindrical member, channels connected lengthwise of and at the inner sides of the bearing shoes, said plate having

arms extending into said channels, a coiled compression spring between said plate and the vertical leg to which the housing is attached, a second plate attached to the other end of said cylindrical member and adapted to be secured to a seat carrying standard, a coiled tension spring connected at one end with said vertically positioned leg at a distance from said cylindrical housing, a thin elongated member of sheet metal to one end of which the opposite end of the tension spring is connected, said sheet metal member extending to and partially around the outer side of the housing, and a pin connected with one of said bearing shoes and extending through the housing to which the other end of said thin metal member is connected, said housing having a slot therein through which the pin passes, said slot permitting a rotative movement of said housing about its cylindrical axis, as specified.

2. In a hinge structure, a member having a vertical leg adapted to be attached at the side edge of a movable seat, a cylindrical housing secured at one side of said leg, said housing at its outer end having a closure with a central opening therethrough, a cylindrical member extending through said opening having its axis substantially coincident with the axis of the housing, a plate within the housing secured to the inner end of the cylindrical member, bearing shoes around said plate within the housing bearing against the inner cylindrical walls of said housing, connections extending loosely between said plate and bearing shoes permitting a lengthwise movement of the cylindrical member with respect to the housing and also a limited angular movement with respect thereto, a coiled compression spring between said plate and the said vertical leg to which the housing is secured, a second plate secured to the outer end of the cylindrical member, said second plate being adapted for connection to a seat carrying standard, said housing being rotatable about its axis and around said bearing shoes, and stop means in said housing and carried by said bearing shoes, for limiting the rotative movement of the housing through an arc of approximately 90°.

3. A construction containing the elements in combination defined in claim 2, combined with yielding means resisting the rotation of said housing in one direction, and operating to return said housing to its original position when free to do so.

4. A hinge for theater seats comprising, a member adapted to be attached at the side of a movable seat, said member having a vertical leg, a cylindrical housing permanently secured at the side of said leg, said housing at its outer end being closed and with a central opening through said closure, a cylindrical member of less diameter than the diameter of said opening extending into the housing through the opening, a plurality of bearing shoes of curved form within the housing bearing against the inner curved wall thereof, a plate secured at the inner end of the cylindrical member, channels having spaced apart inwardly extending parallel flanges the channels being connected to the inner sides of the bearing shoes, said plate having arms the outer ends of which are loosely received between the flanges of said channels whereby the plate with the attached cylindrical member may move longitudinally relatively to said channels or be tilted angularly relatively to the axis of the housing, a coiled compression spring between said plate and the said leg to which the housing is

5 attached, the tendency of which spring being to move the seat and housing from said standard and the plate and attached cylindrical member, a second plate secured to the outer end of said cylindrical member adapted to be attached to a seat supporting standard, and stop means carried by the housing against which the flanges of said channels are adapted to engage to limit the turning movement of said cylindrical housing in both directions, whereby the housing rotation is limited to an arc of approximately 90°.

10 5. A construction containing the elements in combination defined in claim 4, said housing having a slot in the wall thereof of approximately 90° in length, a pin connected with a bearing shoe passing outwardly through said slot, an elongated member of thin metal attached at one end to said pin and having an outer end portion lying against the outer curved wall of the housing and then extending tangentially from the housing, and a coiled extension spring connected at one end to the other end of said thin metal member, said spring at its opposite end being secured to said leg at a distance from the housing, as specified.

15 6. A hinge for theater seats or the like comprising, a metal member adapted to be secured at a side edge of a movable seat, said member including a vertical leg, a cylindrical housing secured to said leg, a cylindrical member having its axis substantially in coincidence with the axis of the housing inserted through the outer end of said housing, curved bearing shoes within the housing bearing against the inner curved walls thereof, connections extending loosely between said cylindrical member and the bearing shoes permitting longitudinal movement of the cylindrical member with respect to the housing, spring means between said leg and cylindrical member 20 tending to move the said leg from said cylindrical member, and a means secured to the outer end of said cylindrical member for attachment to a seat standard.

25 7. A construction containing the elements in combination defined in claim 6, combined with yielding means normally holding said housing at a predetermined position with respect to said cylindrical member but permitting rotation of the housing about the cylindrical member on application of force, said yielding means returning the housing to its initial position on release of said force, and stops for holding the housing in said initial position and for limiting the extent of rotative movement thereof away from 30 said position.

35 8. A hinge for theater seats or the like comprising, two metal hinge members adapted to be secured one at the side edge of a seat and the other to a support, one of said members including a cylindrical housing and the other of said members having a cylindrical element, the axis of which is substantially in coincidence with the axis of the housing and inserted through one end of said housing, curved opposite bearing shoes within the housing bearing on the inner curved walls thereof, projections on said cylindrical element, and means on the bearing shoes loosely engaging said projections for rotating the shoes by said cylindrical element relatively to 40 said cylindrical housing and for permitting longitudinal movement of said cylindrical element with respect to the housing and also a tilting angular movement with respect thereto, as specified.

45 9. A construction containing the elements in

combination defined in claim 8, combined with stop means carried by one of said hinge members and engaged by the other, for limiting relative rotative movement of one of said hinge members with respect to the other to a predetermined arc of movement.

10. A hinge for theater seats or the like comprising, two metallic hinge members adapted to be secured one at a side edge of a seat and the other to a support, one of said members including a cylindrical housing, a cylindrical element having its axis in substantial coincidence with the axis of the housing inserted through one end thereof, curved opposite bearing shoes within the housing bearing on the inner curved walls thereof, projections extending from the inner end of said cylindrical element outward toward said bearing shoes, means on said bearing shoes loosely engaging the ends of said projections for rotating the shoes by said cylindrical element relatively to said cylindrical housing and whereby said housing and cylindrical element may have a relative rotative movement with respect to each other, also relative movement in a direction parallel to the axis of said housing and cylindrical element, and may have a relative tilting angular movement with respect to each other, and means for limiting relative rotative movement of the housing and said cylindrical element with respect to each other to a predetermined arc of movement.

11. A hinge structure for turnably mounting a seat member on a chair's standard member, or the like, said structure comprising a hollow cylinder approximately horizontal axially mounted on one of said members, a curved shoe rotatably

bearing on the inner surface of the cylinder and having angularly spaced channels parallel with its axis, and a spindle mounted on the other of said members extending approximately horizontally into the cylinder spacedly therefrom and having angularly spaced pairs of opposite radial arms the arms of one pair loosely engaging the shoe's inner surface and the arms of the other pair loosely engaging in the respective channels for rotating the shoe relatively to the cylinder in the seat member's turning movement and for permitting relative axial movement of the cylinder and spindle and non-alignment of their axes.

15 5 10 20 25 30 35 12. A hinge structure for turnably mounting a seat member on a chair's standard member, or the like, said structure comprising a hollow cylinder approximately horizontal axially mounted on one of said members, a curved shoe rotatably bearing on the inner surface of the cylinder and having angularly spaced channels parallel with its axis, and a spindle mounted on the other of said members extending approximately horizontally into the cylinder spacedly therefrom and having angularly spaced pairs of opposite radial arms the arms of one pair loosely engaging the shoe's inner surface and the arms of the other pair loosely engaging in the respective channels for rotating the shoe relatively to the cylinder in the seat member's turning movement and for permitting relatively axial movement of the cylinder and spindle and non-alignment of their axes, and a spring pressing between the cylinder and spindle axially thereof.

MILFORD T. VANDERVOORT.
